(57) **CLAIM**

The ornamental design for a stopping tool for a radio controlled vehicle, as shown and described.

DESCRIPTION

FIG. 1 is a top perspective view of a stopping tool for a radio controlled vehicle showing my new design with a generic shown in phantom;

FIG. 2 is a top plan view thereof;

FIG. 3 is a bottom plan view thereof and a reverse view of FIG. 2;

FIG. 4 is an end plan view thereof;

FIG. 5 is an end plan view thereof with the opposite side being a reverse view of FIG. 4;

FIG. 6 is a side view thereof with the opposite side; and,
FIG. 7 is a side view thereof with the opposite side being a
reverse view of FIG. 6.

The broken line showing of a portion of a vehicle is for
illustrative purposes only and forms no part of the claimed
design.
